APPARATUS FOR DISTILLING OIL.

Application filed December 14, 1922. Serial No. 608,997.

This invention relates to apparatus for distilling oil and, more particularly, to apparatus for scraping and removing deposits of tarry and carbon containing substances from the interiors of stills.

In the operation of oil stills, particularly of stills in which heavy hydrocarbons are heated and distilled under pressure, substances such as coke, tar and similar carbonaceous material are formed and deposited on the inner surface of the still. As the substances which form the deposits are poor conductors of heat, the layer thus formed resists the passage of heat from the still walls to the body of oil in the still and interferes with the heating and distillation of the oil. Moreover, if a layer of such substances is permitted to remain on those portions of the still subjected to the intense heat of the furnace, particularly when the still is operated continuously or over long periods of time, the still walls may become overheated and weakened sufficiently to cause bursting or rupturing of the still, and through the escape of oil create danger of disastrous fires. The removal of the deposits during distillation, however, involves considerable difficulty, as sticky, adhesive substances are formed in the deposit which cling to stirrers and scrapers of the ordinary type and, as the material hardens, encases the scraping apparatus in a hard, solid mass and renders its further action ineffective.

An object of the present invention is to provide a means for maintaining the surfaces of stills and similar apparatus substantially free of such deposits or to continuously remove them as they form.

Another object of the invention is to provide a scraping device which is substantially self cleaning during operation.

A further object of the invention is to provide a scraping mechanism positively anchored to the still in such a manner that it may freely expand and contract relatively to the walls of the still.

Further objects and features of the invention are the provision of self cleaning scrapers exposing a minimum of surface on which deposits may form, of weighted scraper blades in which the weighting means is integral with or attached to the scraper blades, and in which the blade supporting means serves to

scrape the exposed surfaces of the blades with each scraping cycle. 55

With these and other objects in view, the invention comprises the apparatus described and set forth in the following specification and claims.

The various features of the invention are 60 illustrated in the accompanying drawings, in which:

Fig. 1 is a sectional plan view of a still and 65 scraping mechanism illustrating a preferred form of the invention,

Fig. 2 is a sectional elevation of the still and scraping mechanism illustrated in Fig. 1.

Fig. 3 is a sectional view of the still and 70 scraping mechanism taken on line 3-3 of Fig. 1,

Fig. 4 is a sectional view of the still and 75 scraping mechanism taken on line 4-4 of Fig. 1,

Fig. 5 is a detail sectional view of scrapers and holders therefor forming a part of 75 the scraping mechanism illustrated in the above figures,

Fig. 6 is a plan view of the scraper blades and holding means shown in Fig. 5, and

Fig. 7 is a detail view of a rake forming 80 a part of the sediment removing mechanism of the present invention.

In the present invention, the sediment of coke, tar, carbon and similar substances forming on the still bottom are scraped loose 85 at frequent intervals and pushed toward an outlet by means of scraper blades passing over the still bottom. The blades are mounted to permit a slight vertical movement and the weight of the blades is supported by the still bottom, a suitable cutting edge being formed on the lower edge of the blades to permit them to sink through the deposited substances into contact with the still bottom. To provide a suitable sliding support the blades are preferably loosely mounted in travelling box like or hollow holders having slots through which the blades project. The weights for the blades may be enclosed in these holders and thereby protected from contact with the 90 contents of the still.

The blades and blade holders pass over the still bottom in an upright position and, upon reaching the end of their travel are inverted and carried through the upper portion of the 105 still to their starting position by means of

endless conveyer chains. As the holder and blades are inverted in this return movement, the weight of the blades draws them downwardly in their inverted position and the exposed portions of the blades are drawn into the holder, the faces of these portions being thereby scraped against the adjacent edges of the guiding slots which act as scraping edges and remove any substance adhering to the faces of the blades. The holders are further guided in their movement by a pair of endless or closed tracks paralleling the circuits of the chains. The chains and tracks are supported on a suitable framework anchored at one place in the still in such a manner as to permit a relative expansion and contraction between the length of the frame and the still walls as the temperatures of these parts change.

In the accompanying drawings, an embodiment of the invention is illustrated as applied to a horizontal, cylindrical still 10 having an oil inlet 12 at one end and, at the opposite end having outlets 14 and 15 through which unvaporized oil, tars, carbon and other substances of similar character formed in the still may be removed. A vapor outlet pipe 16 is also provided in the top of the still. In stills of this type, the end portions of the still rest on the walls of the furnace and thereby protect the still walls adjacent the inlet and outlet pipes from direct contact with the heat of the furnace to which the lower or bottom portion between the ends is subjected.

The carbon, tars, and other sediment collecting or forming on the heated bottom portion of the still is loosened and pushed toward the outlet 14 at frequent intervals by weighted scraper blades 18 and 20 which are supported in an upright position and moved forwardly over the still bottom by means of travelling holders 22. The blades 18 and 20 are arranged to slide individually in a vertical direction on the holders, within limits, and the weight of the blades is supported on a cutting edge 24 supported on the still bottom. For this purpose the holder 22 is made hollow or of a box like cross section and the top wall 26 and bottom wall 28 of the holder are provided with aligned slots 30 and 32 through which the blades 18 and 20 project. (See Figs. 5 and 6). The dimensions of the slots are sufficiently large to permit the blades to slide freely up and down in close contact with the edges of the slots.

The blades are independently slidable in the slots 30 and 32 and are caused to sink through any sediment on the still bottom and contact with the surface of the bottom by means of weights 34 mounted on the portions of the blades within the hollow portion of the holder 22 and thereby protected from contact with the contents of the still. Each blade is provided with an individual weight sufficient to force the blade through the sludge

or sediment on the still bottom and to permit the blades to rise when they pass over any local protuberance or to accommodate their positions individually to any local irregularities in the surface of the still bottom.

The holders are shaped to correspond to the shape of the still bottom and when passing in a scraping position to move at a short distance above the bottom. For this purpose an arcuate holder is used in cylindrical stills and extends over those portions of the bottom and side walls on which adhering deposits tend to form. The blades 18 and 20 are arranged in staggered relation in two rows in such manner that each portion of the still bottom is uniformly and efficiently scraped.

The holders 22 are moved over the surface of the still by means of parallel endless chains 36 and 38 trained over a pair of driving cog wheels 40 and 42 at the outlet end of the still and a pair of idler cog wheels 44 and 46 mounted on a shaft 47 at the opposite or inlet end of the still. The holders are secured to the chains by means of struts 48 which are connected between brackets 52 on the holders and a link in each of the chains. The driving wheels are supported on, and driven by a shaft 56 which is supported at one end in a bearing 58, mounted on the wall of the still by means of a bracket 59 and passes through a bearing 60 and stuffing box 61 on the opposite wall of the still to a suitable source of power outside of the still. The shaft 56 and wheels 40 and 42 are driven in such a direction as to draw the lower lengths of the chains 36 and 38 and the holders and blades 18 and 20 over the still bottom toward the outlet 14.

As the portion of the chains to which the holders are attached pass over the wheels 40 and 42, the holders are carried around the wheels to an inverted position on the top of the wheels and pass in this inverted position to the idler cog wheels 44 and 46. As the holders are inverted the scraping blades 18 and 20 fall downwardly, drawing the portion of the blades projecting through the slots 32 in the wall 28 into the interior of the holders 22 until the weights 34 reach the wall 26 and prevent the further fall of the blades. The weights are of such dimensions that very nearly the entire projecting portion of the blades will be drawn into the holders as the weights reach the wall 26. As the blades pass over the edges of the slots 32 these edges scrape any adhering substance from the faces of the blades and thus prevent the accumulation and hardening of an encasing layer of material. Also the blades 18 are guided or positioned during their movements by the edges of the slots in the wall 26. As the holders and blades pass over the wheels 44 and 46 to their starting position at the under side of the wheels and in proximity to the inlet end, the holders are returned to their upright position. The

blades thereupon slide downwardly through the slots 32 under the action of the weights 34 until the lower cutting edges 24 reach the still bottom.

- 3 The holders 22 are further guided in their movement and are held in suitable position relative to the still bottom by means of a pair of closed or endless tracks in spaced relation at the opposite ends of the holders. The 10 holders are mounted on the tracks 62 and 64 by means of carriages 66 and 68, one at each end of the holders, and each carriage is provided with an upper pair of wheels 70 and a lower pair of wheels 72 which ride on opposite 15 sides of horizontal webs 74 of the tracks 62 and 64. The tracks are substantially parallel to the chains 36 and 38 and have upper and lower horizontal reaches 76 and 78, on which the weight of the holders and blades is supported as they pass between the cog wheels, 20 and semi-circular end connecting portions 80 and 82 which serve to guide the holders in passing around the cog wheels from one horizontal length to the other.
- 25 The tracks 62 and 64 further serve as a part of a framework for holding the shafts 56 and 47 in their proper positions. The remaining portion of the frame is formed by vertical posts 84 and diagonals 86 between the horizontal portions 76 and 78 and cross beams 88 extending between the posts 84 and serving to hold the tracks in their properly spaced positions relative to each other.

As the still walls are heated more rapidly 30 than the frame work on which the scraping mechanism is supported and are usually at a somewhat higher temperature during distillation, the frame is so mounted in the still as to permit a relative expansion and contraction 35 between it and the still walls. For this purpose the frame is anchored or fastened to the still walls at one point or position in the length of the still and extends longitudinally 40 in a sliding relation to the still walls throughout the remaining length of the frame. The frame is preferably anchored to the still walls at the driving shaft 56 by means of a pair of vertical plates 90, one of which is supported 45 by the bearing 58 and bracket 59 and the other of which is supported by the stuffing box 61 and bearing 60. The free length of the frame 50 is supported by means of wheels or rollers 92 mounted on the lower sides of the tracks 62 and 64 by means of brackets 94 and riding on the adjacent walls of the still. As the frame 55 is anchored at only one transverse axis a free relative expansion and contraction between the remaining length of the frame and the still walls is permitted.

60 The idler shaft 47 and the cog wheels 44 and 46 are mounted on the frame by means of vertical plates 96 extending between the upper and lower lengths of the track at the end opposite the shaft 56 and carrying bearings 98 in which the ends of the shaft 47 are

mounted. The chains are thus supported by the track frame and may expand and contract with the frame independently of the still walls.

Material which has been detached from the 70 bottom of the still by the scraper blades 18 and 20 may pass between the blades and remain on the still bottom. This and other material which may lie loosely on the walls of the still should be removed through the outlet 75 14. To this end the scrapers 18 and 20 are followed by a series of hoes 100 extending in a continuous transverse line throughout the surface of the still over which the scrapers pass. The hoes are drawn forwardly over 80 the still by means of an arcuate shaped frame 102 attached to the chains 36 and 38 by means of brackets 104 and struts 106 similar to those of the holders 22. The hoes 100 are pivotally attached to the frame 102 by means of arms 85 108 pivotally attached to the frame 102 at their forward ends, and the weight of the hoes is borne on the still bottom in such a manner that the hoes may rise individually when an obstruction is encountered. The frames 90 102 are also guided in their movement by means of carriages 110, Figs. 2 and 3, having pairs of wheels 112 and 114 riding on the tracks 62 and 64. The hoes are so mounted 95 on the frame 102 that when inverted the arms of the hoes rest on a horizontal flange 116 which limits their downward swing.

Through the above invention the exposed or scraping portions of the scraping blades 18 and 20 are drawn through the slots 32, at 100 each scraping cycle and any viscous material adhering to the faces of the blades is removed. The weighted or moving portions of the blades are protected to some extent by the holder 22 from direct contact with the contents of the still and a side 118 of the holder 105 may be readily taken off to remove any deposits which might interfere with the free operation of the blades. This arrangement of the blades also enables a holder to be used 110 which is of smooth outer surface which may be easily cleaned. The frame construction also provides a mounting for the scraping apparatus which avoids all tendency to place 115 the still walls or the frame under strains due to unequal expansion and contraction as the still is heated or allowed to cool.

Having thus described the invention, what is claimed as new is:

1. Apparatus of the type described which 120 comprises, a still, scraper blade holding means adapted to be moved over the bottom surface of said still, said holding means being hollow and having slots in its opposite walls, scraper blades extending through and slidably in said 125 slots and weights attached to said blades within said holder and slidably in said holder with said blades.

2. Apparatus of the type described which 130 comprises, scraping blades adapted to be car-

ried over a surface in substantially vertical position, a hollow holding means for said blades having aligned slots in its opposite walls through which said blades project, 5 weights in said hollow holder attached to and slideable with said blades and means for moving said holder and blades over a surface to be scraped and for returning them in inverted position.

10 3. Apparatus of the type described which comprises, a hollow holder having walls adapted to assume superposed positions and aligned slots in said walls, a blade extending through said holder and projecting through 15 said slots, and a weight in said holder acting on said blade to move said blade in said slots.

4. Apparatus of the kind described which comprises, a scraping blade, a hollow holder having positioning and scraping edges at 20 the sides of said blade and a weight attached to said blade and slideable between said edges.

5. Apparatus of the type described which comprises, a scraping blade, a holder having positioning and scraping edges at the sides 25 of said blade, and a weight attached to said blade to move the blade past said edges when the position of said blade is inverted, said holder including means for protecting said weight from contact with the material 30 through which said apparatus moves.

6. Apparatus of the type described which comprises, scraper blades having weighted 35 portions, means for holding and carrying said blades in staggered position over a surface to be scraped and having guiding and scraping edges adjacent the faces of said blades, said means enclosing the weighted portions of said blades and permitting the end portions of said blades to project and slide past 40 said edges under the action of the weights of the blades.

7. Apparatus of the type described which comprises, a blade holder of substantially 45 rectangular cross section, having slots in its opposite walls, scraper blades extending across said holder and projecting through said slots, and weights mounted on said blades within said holder.

8. Apparatus of the type described which 50 comprises, a cylindrical still, a scraper blade holder curved to conform to the cross sectional curvature of the bottom of said still, said holder being hollow and having slots in its walls, scraper blades extending through 55 said holder and projecting through said slots, weights mounted on said blades within said holder, and means for moving said blades and holder over and in proximity to the bottom of said still and for inverting said blades 60 and holder and returning them out of contact with the bottom of said still.

9. Apparatus of the type described which 65 comprises, a still having an outlet, a frame corresponding to the curvature of the bottom of said still, means for moving said frame

over the still bottom towards said outlet and for returning said frame out of proximity to said still bottom to its starting position, and hoes pivotally attached to said frame, to rest on the bottom of said still and 70 extending in a continuous line transversely over said still bottom.

10. Apparatus of the type described which comprises a still, a scraper frame mounted within the still, a series of scraper holders 75 shaped to conform to the cross sectional shape of the bottom portion of the still movably mounted in the frame, a series of scraper blades mounted in the holders, a series of cleaner holders shaped to conform to the 80 cross sectional shape of the bottom portion of the still movably mounted in the frame, and hoes pivoted to the cleaner holders in a position to have their cleaning edges in 85 contact with the bottom portion of the still when the cleaner holder is in the lower portion of the still.

11. Apparatus of the type described which comprises a still, a scraper frame mounted within the still, a series of scraper blade 90 holders shaped to conform to the cross sectional shape of the lower portion of the still and movably mounted in the said frame, a series of scraping blades movably mounted in said frame, a series of weights mounted on said blades arranged to force the cutting edges of the blades into contact with the bottom portion of the still when the blade holder is moving adjacent to the bottom of the still, a series of cleaner holders movably 100 mounted in said frame and arranged alternately between scraper blade holders, said cleaner holders having a series of hoes pivotally mounted thereto with their cleaning edges extending substantially transversely 105 across the lower portion of the still, and means for positively moving the holders in an annular path longitudinally of the still to move the scraping blades and hoes lengthwise of the bottom of the still. 110

12. A still comprising a shell provided adjacent one end with an outlet through which sediment can be removed from the still, a scraping device arranged inside of the still and adapted to be moved longitudinally of the same for removing sediment from the bottom of the still and discharging it through said outlet, a carrier for said scraping device arranged transversely of the still, endless chains for actuating said carrier, an idler shaft provided with sprockets around which said chains travel, a supporting frame for said idler shaft arranged inside of the still and having one end fixed to the still, the other end of said frame being disconnected from the still, and a roller bearing intermediate the free end of said frame and the shell of the still for supporting the weight of the frame while permitting relative motion between frame and the shell. 125 130

13. A still comprising a shell provided adjacent one end with an outlet through which sediment can be removed from the still, a scraping device arranged inside of the still and adapted to be moved longitudinally of the same for removing sediment from the bottom of the still and discharging it through said outlet, a carrier for said scraping device arranged transversely of the still, end-
10 less chains for actuating said carrier, an idler shaft provided with sprockets around

which said chains travel, a supporting frame for said idler shaft arranged inside of the still and having one end fixed to the still, the other end of said frame being disconnected 15 from the still, and continuous tracks on said frame on which the scraping device carrier travels, and a roller bearing intermediate the free end of the frame and the shell of the still.

In testimony whereof I affix my signature.
HENRY S. PETTINGILL, JR.
